SUCTION AND FLUSHING MASSAGE DEVICE

Dorothy Beatman, Chicago, Ill.

Application April 27, 1949, Serial No. 89,979

(CL 128—66)

This invention pertains to a new and improved therapeutic device for aiding and assisting the body to relieve itself of waste accumulations in the skin surface. It is particularly directed to an improved device for promoting circulation of blood in the skin surfaces of the human body.

There are many devices for promoting circulation of blood in the epidermis of the human body. Most of these are based either upon either mechanical or medicinal means. This invention is primarily concerned with the mechanical types. Most of the mechanical types are based upon the principle of vibrating a disc or some other type of shape that is held against the skin surface. Such rapidly vibrating disc or device presses to and fro on the surface of the skin of the body and stimulates the flow of blood within the skin. In course of such action, oil, dirt, deposits of grease, blackheads, etc., are loosened under the effect of the vibrator and in many cases pop out to the surface where they can be readily removed without harm and danger to the skin itself. However most vibrators of the contact type instead of acting as a device to remove such blemishes on the surface of the skin have a tendency to grind these into the skin and instead of helping the skin to clear itself, impart additional burdens to it and may be the cause of dangerous skin effects leading to skin cancer and other serious disorders.

Again some devices used for promoting circulation depend upon liquid such as water, alcohols, etc. carrying therein generally in solution form some type of medicant to open the pores and cause a slight erythema but without any benefit of real value and worth.

It therefore is an object of my invention to provide a massaging device that will increase circulation of blood within the surface of the living human body.

Another object of my invention is to provide a massaging device of therapeutic value which removes sweat and detritus found within the pores of the body.

A still further object of my invention is an improved massaging device which not only opens the pores but also flushes away the dirt and grime found thereon.

A further and additional object of my invention is to provide a massaging device for promoting the circulation of blood in the surface of the body which is economical to produce and effective in its action.

These and other objects, adaptations, varia-

tions, extensions and modifications will be clearly apparent to one skilled in this art particularly in view of the clear, lucid and detailed description given hereinbelow of the preferred embodiment for purely exemplary purposes and which is not to be construed directly or indirectly as a limitation of the fundamental concepts underlying my invention as claimed or illustrated in the attached drawing forming a part hereof.

For purposes of clarity, characters used in the drawings to point out the elements underlying my invention are the same as used hereinbelow to identify the said elements in relation to others.

Therefore,

Figure 1 shows my improved device in use.

Figure 2 shows in detail my improved device in which one of the massage applicators is shown in section, while

Figure 3 shows the face of the individual applicator.

My improved massaging device consists of a hose 10 having on one end thereof a suitable coupling 12 which is capable of being attached to a supply of water that can be regulated as to flow and temperature. Faucets of this type are well known and are not a part of my invention. The other end of the said hose 10 terminates in a bifurcated hose divider 14 that forms preferably an integral part of the tubes 16 and 18 attached to spray head drums 20 and 22 respectively through nipples 24 and 26 respectively, the latter forming preferably an integral part of said spray head drums 20 and 22.

On the said spray head drums 20 and 22 are placed circular sheets 28 of the proper size to fit over the drums 20 and 22. The sheets 28 have therein a series of perforations 30 placed preferably equidistant from each other in a circle about the outer edge of a suction cup 32. The suction cup 32 and the circular plate or sheet 28 are retained or fastened together by means of a rivet 34 or any other suitable means 45 by which the two can be joined fixedly. The entire assembly is held together by means of a threaded annular ring 36 which engages threads 38 on the spray head drums 20 and 22.

The suction cup 32 consists of an open semi-elliptical or hemispherical hollow shape made preferably of such plastic or elastic material as rubber. This portion of my invention is placed against the body of the user and forced inwardly until all of the air within the space 55 encompassed by the shape is practically ex-

hausted. It is then removed. In the course of removal, a vacuum is created within the shape and the pores of the skin are forced apart to expel any impurities therein. There is always a small amount of grime, sweat, air, blackheads, debris of face powder, rouge, etc. within the pores. I have found that the repeated application of such suction not only removes the accumulated wastes and grime in the skin but also aids in improving the circulation of the blood in and about the area under treatment by my improved massaging device.

In use, I adjust the temperature as well as flow of water from the faucet through the hose 10 into the spray heads 20 and 22. I grasp each of 15 the spray heads in each hand and apply alternately one spray head and then the other spray head to the selected portions of the body. The water emerges through the perforations 30 and sprays on the skin. The suction cup 32 is then 20 applied against the skin and forced downwardly until a suction is created beneath the cup. The skin moistened with water helps to provide a better seal for the rim of the suction cup 32. In the meantime while the suction is being applied 25 water is constantly flushing the skin area about the suction cup 32. If relatively hot water is used the circulation of blood within the skin under the water is improved, the sweat pores open because of the therapeutic effect of heat and as the suction is removed all of the waste 30 materials and accumulations such as blackheads, acne and other irritations are either removed or considerably alleviated so that the skin becomes clearer and assumes a tone of health and vigor.

By alternate pressing of the spray heads 20 and 22 with sufficient force against the body, the stream of water will be forced through the perforations 30 in the other spray head since the flow in the perforations 30 on the spray head in contact with the body will be diminished or completely shut off depending on the amount of force to the spray head and on the part of the body to which the spray head is applied.

It is apparent that the materials used in my 45 massaging device can vary considerably and can be made from metal, plastic, rubber, etc. I prefer to use rubber since it is admirably suited in its characteristics as the ideal material.

Though the embodiment of my invention as

described hereinabove and illustrated in the attached drawings is the preferred one it nevertheless is not my intention to be limited to such preferred embodiment since obviously the same can be varied widely and still be within the scope and spirit of the hereunto appended claims which define the fundamental concepts underlying my invention.

I claim:

10. 1. An improved massage and therapeutic device comprising a hose, a means on one end of said hose to attach it to a source of supply of fluid, the other end of said hose terminating in a bifurcated assembly of at least two therapeutic heads, each of the said heads comprising a plate, a means to spray water through said plate, and a suction cup attached to central portion of the plate of the said means to spray water, the said suction cup protruding beyond the said plate whereby suction and fluid spray can be applied simultaneously to different adjacent areas of the body.
20. 2. In the product of claim 1, perforations for fluid exit in the said spray plate that are disposed about the said suction cup.
25. 3. A therapeutic massaging spray head comprising a means for ingress of water to the spray head, a spray head attached to said means for ingress of water, a flat plate attached to said head, a suction cup on the said plate protruding therefrom, and perforations in said plate for egress of water about the outside edge of said suction cup.
